UNITED STATES PATENT OFFICE.

MOSES MORRIS, OF BALTIMORE, MARYLAND.

UNION SUIT.

1,098,960.

Specification of Letters Patent.

Patented June 2, 1914.

Application filed July 28, 1913. Serial No. 781,611.

To all whom it may concern:

Be it known that I, MOSES MORRIS, a citizen of the United States, residing at Baltimore, in the State of Maryland, have invented certain new and useful Improvements in Union Suits; and I do hereby declare the following to be a full, clear, and exact description of the invention, such as will enable others skilled in the art to which it appertains to make and use the same.

This invention relates to union suits. Heretofore these suits have been constructed relatively tight at the crotch with the lower end of the back slit terminating rear of the crotch so that great inconvenience is imposed upon the wearer at times in that the entire removal of the suit is necessitated.

It is therefore the object of this invention to provide a union suit in which the crotch portion is constructed relatively full and much longer and the back slit extended medially through the crotch so that a portion of said slit will extend up the front of the garment, such a construction obviously insuring convenience and flexibility to the wearer at all times.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a front elevation of a union suit constructed in accordance with the invention; Fig. 2, a rear elevation of same; Fig. 3, a vertical central section of the suit; Fig. 4, a bottom view of the suit with the leg portions thereof spread apart, and Fig. 5, is a view showing the forms or blanks of the lower rear sections of the suit.

Referring to the drawing the suit is shown as comprising front sections 10 and 11; and rear sections 12, 13 and 14. The front sections 10 and 11 each comprise a body portion 15 and a leg portion 16, said sections 10 and 11 being connected together only at the inner ends of the leg portions 16, as at 17 so as to form a front slit 18. Mounted along the edge of the section 10 adjacent the slit 18 are buttons 19, while button holes 20 are

formed in the edge of the section 11 along the slit 18 for the reception of the buttons 19 respectively and whereby the opening and closing of the slit 18 is controlled. The upper back section 12 has its longitudinal edges stitched to the outer longitudinal edges of the upper portion of the sections 10 and 11, suitable provision being made for the insertion of sleeves 21 and 22. The top transverse edge of the section 12 is stitched to the top transverse edges of the sections 10 and 11 as will be obvious. The lower back sections 13 and 14 of the suit each include a body portion 23 and a leg portion 24 and the outer longitudinal edges of the sections 13 and 14 are stitched to the outer longitudinal edges respectively of the sections 11 and 10, while the upper transverse edges of the sections 13 and 14 are connected to the lower edge of the section 12 by means of a flexible insertion 25. The body portions 23 of the sections 13 and 14 are provided at the inner side of their lower ends with inwardly and downwardly directed extensions 26 which are connected together at their outer ends as at 27 whereby a long rear slit 28 is produced together with a very full crotch. The inner edges of the leg portions 24 including the lower edges of the extensions 26, and the inner edges of the leg portions 16 are connected together by a continuous flexible insertion 29.

It will be noted that the extensions 26 are V-shaped and have outwardly curved lower edges 30 respectively and outwardly curved upper edges 31 respectively. The peculiar shape of these extensions 26 just described results in the production of a very extensive and full crotch and at the same time throws such fullness forward when the completed garment is on the wearer so that the crotch may be raised at the front side of the garment and the lower end of the slit 28 correspondingly raised which is a distinct advantage to the wearer.

What is claimed is:—

1. A union suit comprising a body portion, right and left front leg sections formed integral with the body, and right and left rear leg sections having laterally extending tongues formed on their inner side edges, the lower inner side edges of the rear leg sections and the adjacent edges of the tongues being stitched to the inner side edges of respective leg sections and the remaining edges of said tongues left free whereby a

relatively full crotch and long slit is provided.

2. A union suit comprising a body portion, right and left front leg sections formed integral with the body, a continuous insert stitched to the inner edges of said front leg sections, and right and left rear leg sections having laterally extending tongues formed on their inner side edges, the lower inner side edges of the rear leg sections and the

adjacent edges of the tongues being stitched to the insert and the remaining edges of said tongues left free whereby a relatively full crotch and long slit is provided.

In testimony whereof, I affix my signature, in the presence of two witnesses.

MOSES MORRIS.
